UNITED STATES PATENT OFFICE.

CORNELIUS D. EHRET, OF PHILADELPHIA, PENNSYLVANIA.

ELECTRONIC APPARATUS.

1,419,547.

Specification of Letters Patent. Patented June 13, 1922.

Application filed November 12, 1918. Serial No. 262,183.

To all whom it may concern:

Be it known that I, CORNELIUS D. EHRET, a citizen of the United States, residing in the city and county of Philadelphia, State of Pennsylvania, have invented a new and useful Electronic Apparatus, of which the following is a specification.

My invention relates to thermionic or electronic devices which may be put to any suitable or desired use, as for example signaling, telegraphy or telephony, either in radio or wireless systems or in systems in which the energy is transmitted by conductors extending between transmitting and receiving stations.

My invention resides in an electronic or thermionic device comprising a body emitting electrons which bombard a cathode which reemits electrons to an anode, the cathode completely isolating the anode and the electron emitting body from each other, as by sealing evacuated chambers containing the anode and the body from each other.

My invention resides in further features hereinafter described.

For an illustration of some among the many various forms my invention may take, reference may be had to the accompanying drawing, in which:

Fig. 1 is an elevation of my electronic device, partly in section, and a diagram of circuit arrangements in which it may be employed.

Fig. 2 is a similar view of my device and a diagram of other circuit arrangements in which it may be employed.

Referring to Fig. 1, A is a vessel, tube or bulb of glass or any other suitable material divided by the cathode K into two chambers V and V¹, both of which and particularly V, are preferably closed to the outer atmosphere. The cathode K may be of any suitable material, preferably refractory metal as platinum or tungsten, and in the example illustrated is in the form of a thin plate sealed throughout its periphery at k, whereby it completely seals chambers V and V¹ from each other and forms a wall common to them.

The chambers V and V¹ may be evacuated to any suitable or desirable equal or unequal degrees, as by exhausting at v and v¹. The chamber V is preferably exhausted substantially completely or to such degree that pure electron discharge takes place therein, particularly when the electron emitting body

F is, as in the example illustrated, a filament of platinum, tungsten, carbon or any other suitable material, brought to suitably high temperature or incandescence by current as from the source b, the variable resistance r serving to vary the primary electron emission.

It will be understood, however, that in the chamber V positive ions in any suitable number may be present, as by having therein any suitable gas or gases, vapor or vapors, or mixtures of gas and vapor; and the filament F may be coated with any suitable oxide, as calcium, strontium or barium oxide, or any suitable mixture of two or more of such oxides.

Similarly the chamber V¹ may be exhausted to such high degree that substantially pure electron discharge obtains from cathode K to the plate or anode P. Or in chamber V¹ positive ions may be utilized, as by having therein any suitable gas or gases, vapor or vapors, or mixtures of gas and vapor; and the side of cathode K in chamber V¹ may be coated with any suitable oxide, as calcium, barium or strontium oxide, or any suitable mixture of two or more of such oxides.

The cathode K is, in the example illustrated connected to the filament F through a variable portion of the source of current or battery B, whereby cathode K is normally held at any suitable potential positive with respect to filament F. Similarly the anode or plate P is connected through the transformer primary p and a variable portion of the source of current or battery B with cathode K, whereby anode P is normally held at any suitable potential positive with respect to cathode K.

The body F emits electrons which bombard or impinge upon the cathode K which in consequence becomes an electron emitting body. The number of electrons so reemitted may greatly exceed the number of electrons emitted by body F, and so permit or cause a large current between anode P and cathode K. That current may be caused to vary in amplitude or fluctuate by varying the potential of electrode or grid G¹, which may be connected to cathode K through transformer secondary s¹ and the potentiometer D which serves in known manner normally to hold grid G¹ at any suitable potential. When a telephonic, oscillating or other varying or fluctuating current is passed through trans-

former primary p^1 , the potential of grid G^1 , and therefore the large current in the circuit of anode P , is correspondingly varied. And that current in transformer primary p may induce an alternating or fluctuating current similarly varying in the secondary s .

The amplitude of the current in the circuit of anode P may also be varied by varying the potential of the electrode or grid G , which will vary the intensity of bombardment of cathode K by electrons emitted by body F , with consequent variation in the number of electrons reaching anode P from cathode K , provided cathode K has suitably delicate proportions e. g., is suitably thin to respond quickly or with accuracy to variations in its bombardment by electrons from body F . The potential of grid G , connected through potentiometer D^1 and transformer secondary s^2 to body F , may be varied by passing through transformer primary p^2 a fluctuating or varying current.

A fluctuating or alternating current of inaudible high frequency from source a may be passed through primary p^1 and cause variations of potential of grid G^1 and so cause in secondary s , connected to a radiating antenna or equivalent or to a wire circuit, a far larger current, of inaudible high frequency, whose amplitude may be varied in accordance with speech by passing through primary p^2 a current from battery b^1 modulated by microphone m ; and cathode K for this purpose must be of such delicate proportions, e. g., so very thin, that it will re-emit to anode P a stream of electrons varying in accordance with speech.

In Fig. 2 the electronic or thermionic device is of the character described in connection with Fig. 1. In this case the anode P , cathode K and grid G^1 are associated in an oscillating circuit comprising the transformer primaries p and p^3 in series with the variable condensers C and C^1 between anode P and cathode K , the grid G^1 being connected to cathode K through transformer secondary s^3 and variable condenser C^2 . A variable source of current or battery B^1 is connected through choke coils or impedances c and c^1 to anode P and cathode K . The body F and cathode K are in circuit with a variable source of current or battery B^2 through the transformer primary p^4 whose secondary s^4 connects cathode K through potentiometer D with grid G^1 . Microphone m and source of current b^1 are in circuit with transformer primary p^2 whose secondary s^2 connects body F through potentiometer D^1 with grid G .

With body F emitting electrons which impinge upon cathode K the latter emits to anode P secondary electrons; and oscillations, for example of frequency above audibility, are produced in the oscillating circuit and impressed by transformer second-

ary s upon a radiating antenna, or equivalent, or upon a wire circuit. The amplitude of the oscillations are varied in accordance with speech by microphone m which causes variation of potential of grid G and therefore variation of current in transformer primary p^4 in accordance with speech; and in consequence the potential of grid G^1 is varied in accordance with speech by the transformer secondary s^4 , with resultant variation of amplitude of the high frequency oscillations in accordance with speech. The arrangement may be considered as amplifying apparatus, the effects in circuit mb^1p^2 being enlarged in circuit Kp^4B^2F and still further amplified in the oscillating circuit including anode P and cathode K . Additional amplification may also be effected if cathode K is of sufficiently delicate proportions, as extremely thin, to vary the electron emission therefrom due to variation by grid G of the number of electrons from body F bombarding cathode K .

What I claim is:

1. Thermionic apparatus comprising a plurality of cooperating thermionic devices each comprising an anode, a cathode and a grid, the anode of one of said devices being the cathode of another of said devices, the grid-cathode circuits of said devices being independent of each other, and a coupling between circuits of said devices.

2. Thermionic apparatus comprising a plurality of cooperating thermionic devices each comprising an anode, a cathode and a grid, the anode of one of said devices being the cathode of another of said devices, a transformer primary in the anode circuit of said one of said devices, and the transformer secondary in the grid circuit of said other of said devices.

3. Thermionic apparatus comprising a plurality of cooperating thermionic devices each comprising an anode, a cathode and a grid, the anode of one of said devices being the cathode of another of said devices, a coupling between circuits of said devices, and means for normally holding each of said grids independently of each other at a predetermined potential.

4. Thermionic apparatus comprising a plurality of cooperating thermionic devices each comprising an anode, a cathode and a grid, sources of current for the anode circuits of said devices, the anode of one of said devices being the cathode of another of said devices, the source of current of the anode circuit of said one of said devices intervening between the grid circuits of said devices.

5. An electronic device comprising evacuated chambers, a cathode forming a sealing wall between said chambers, a body in one of said chambers emitting electrons bombarding said cathode, an anode in another of

- 5 said chambers in the stream of electrons re-emitted by said cathode, an electrode between said body and said cathode, and means for varying the potential of said electrode.
6. Thermionic apparatus comprising a plurality of cooperating thermionic devices each comprising an anode, a cathode and a grid, the anode of one of said devices being 10 the cathode of another of said devices, and means for normally holding each of said grids independently of the other at a predetermined potential.
7. An electronic device comprising evacuated chambers, a cathode forming a sealing wall between said chambers, a body in one of said chambers emitting electrons bombarding said cathode, an anode in another of said chambers in the stream of electrons reemitted 15 by said cathode, an electrode between said cathode and said anode, means for varying the potential of said electrode, an electrode between said body and said cathode, and means for varying the potential of said last 20 named electrode.
8. An electronic device comprising evacuated chambers, a cathode forming a sealing wall between said chambers, a body in one of said chambers emitting electrons bombarding said cathode, an anode in another of said chambers in the stream of electrons reemitted 25 by said cathode, an electrode between said cathode and said anode, means for varying the potential of said electrode, an electrode between said body and said cathode, and means for varying the potential of said electrode in accordance 30 with said sound waves.
9. An electronic device comprising evacuated chambers, a cathode forming a sealing wall between said chambers, a body in one of said chambers emitting electrons bombarding said cathode, an anode in another of said chambers in the stream of electrons reemitted 35 by said cathode, an electrode between said cathode and said anode, and means for varying the potential of said electrode in accordance with said sound waves.
- 40 10. An electronic device comprising evacuated chambers, a cathode forming a sealing wall between said chambers, a body in one of said chambers emitting electrons bombarding said cathode, an anode in another of said chambers in the stream of electrons reemitted 45 by said cathode, and means for varying the electron stream between said body and said cathode in accordance with sound waves, said cathode being so proportioned that it reemits to said anode an electron stream varying in accordance with said sound waves.
- 50 11. An electronic device comprising evacuated chambers, a cathode forming a sealing wall between said chambers, a body in one of said chambers emitting electrons bombarding said cathode, an anode in another of said chambers in the stream of electrons reemitted 55 by said cathode, means for varying the electron stream between said body and said cathode in accordance with sound waves, said cathode being so proportioned that it reemits to said anode an electron stream varying in accordance with said sound waves.
- 60 12. An electronic device comprising evacuated chambers, a cathode forming a sealing wall between said chambers, a body in one of said chambers emitting electrons bombarding said cathode, an anode in another of said chambers in the stream of electrons reemitted 65 by said cathode, means for varying the electron stream between said body and said cathode for varying the potential of said electrode.
- 70 13. An electronic device comprising evacuated chambers, a cathode forming a sealing wall between said chambers, a body in one of said chambers emitting electrons bombarding said cathode, an anode in another of said chambers in the stream of electrons reemitted 75 by said cathode, means for varying the electron stream between said body and said cathode in accordance with sound waves, an electrode between said anode and said cathode, and means for varying the potential of said electrode in accordance with said sound waves.
- 80 14. An electronic device comprising evacuated chambers, a cathode forming a sealing wall between said chambers, a body in one of said chambers emitting electrons bombarding said cathode, an anode in another of said chambers in the stream of electrons reemitted 85 by said cathode, means for varying the electron stream between said body and said cathode in accordance with sound waves, an electrode between said anode and said cathode, and means for varying the potential of said electrode in accordance with said sound waves.
- 90 15. The combination with an anode and a cathode, of a body emitting electrons bombarding said cathode, means for varying the electron stream between said body and said cathode in accordance with sound waves, said cathode being so proportioned that it 95
- 100 16. An electronic device comprising evacuated chambers, a cathode forming a sealing wall between said chambers, a body in one of said chambers emitting electrons bombarding said cathode, an anode in another of said chambers in the stream of electrons reemitted by said cathode, means for varying the electron stream between said body and said cathode in accordance with sound waves, an electrode between said anode and said cathode, and means for varying the potential of said electrode in response to variations in said electron stream between said body and said cathode.
- 105 17. An electronic device comprising evacuated chambers, a cathode forming a sealing wall between said chambers, a body in one of said chambers emitting electrons bombarding said cathode, an anode in another of said chambers in the stream of electrons reemitted by said cathode, an electrode between said anode and said cathode, and means for varying the potential of said electrode in accordance with variations of said electron stream between said body and said cathode.
- 110 18. An electronic device comprising evacuated chambers, a cathode forming a sealing wall between said chambers, a body in one of said chambers emitting electrons bombarding said cathode, an anode in another of said chambers in the stream of electrons reemitted by said cathode, an electrode between said anode and said cathode, an oscillating circuit associated with said anode, said cathode and said electrode, means for varying the electron stream between said body and said cathode, and means for varying the potential of said electrode in accordance with variations of said electron stream between said body and said cathode.
- 115 19. The combination with an anode and a cathode, of a body emitting electrons bombarding said cathode, means for varying the electron stream between said body and said cathode in accordance with sound waves, said cathode being so proportioned that it 120
- 125 20. An electronic device comprising evacuated chambers, a cathode forming a sealing wall between said chambers, a body in one of said chambers emitting electrons bombarding said cathode, an anode in another of said chambers in the stream of electrons reemitted by said cathode, an electrode between said anode and said cathode, and means for varying the potential of said electrode in accordance with variations of said electron stream between said body and said cathode.
- 130 21. The combination with an anode and a cathode, of a body emitting electrons bombarding said cathode, means for varying the electron stream between said body and said cathode in accordance with sound waves, said cathode being so proportioned that it

reemits to said anode an electron stream varying in accordance with said sound waves, a grid between said anode and said cathode and independent of said means, and 5 means responsive to variations in the electron stream between said body and said cathode for varying the potential of said grid.

16. The combination with an anode and a 10 cathode, of a body emitting electrons bombarding said cathode, means for varying the electron stream between said body and said cathode, a grid between said anode and said cathode and independent of said means, and 15 means for varying the potential of said grid in response to variations in said electron stream between said body and said cathode.

17. The combination with an anode and a 20 cathode, of a body emitting electrons bombarding said cathode, means for varying the electron stream between said body and said cathode, an electrode between said anode and said cathode, an oscillation-producing circuit associated with said anode, said cathode 25 and said electrode, and means for varying the potential of said electrode in accordance with variations of said electron stream between said body and said cathode.

18. Thermionic apparatus comprising a 30 plurality of cooperating thermionic devices each comprising an anode, a cathode and a grid, the anode of one of said devices being the cathode of another of said devices, and means for normally holding each of said 35 grids independently of the other at a predetermined negative potential.

19. An electronic device comprising a 40 chamber, a cathode and an anode therein, a separate chamber evacuated to a degree suitable for substantially pure electron discharge, said cathode forming a wall common to said chambers, and a body in said separate chamber emitting electrons bombarding said cathode, said first named chamber evacuated to lesser degree than said separate chamber and containing ionizable material.

20. The combination with an anode and a 50 cathode, of a body emitting electrons bombarding said cathode, a grid controlling the electron stream between said body and said cathode, means for varying the potential of said grid for varying said electron stream and thereby the electron stream between said cathode and said anode, a grid independent of said first named grid controlling the electron stream between said cathode and said anode, and means for varying the potential of said second named grid in response to changes of potential of said first 55 named grid.

21. The combination with an anode and a 60 cathode, of a body emitting electrons bombarding said cathode, a grid controlling the 65 electron stream between said body and said

cathode, means for varying the potential of said grid for varying said electron stream and thereby the electron stream between said cathode and said anode, a grid controlling the electron stream between said cathode and said anode, means for varying the potential of said second named grid in response to changes of potential of said first named grid, and an oscillation-producing circuit including said anode and cathode. 70

22. Thermionic apparatus comprising a 75 plurality of cooperating thermionic devices each comprising an anode, cathode and grid, the anode of one of said devices constituting the cathode of another of said devices, the grids being independent of each other, means for varying the potential of the grid of said one of said devices, and means responsive to changes in the anode current of said one of said devices varying the potential of the 80 grid of said other of said devices.

23. Thermionic apparatus comprising a 85 plurality of cooperating thermionic devices each comprising an anode, cathode and grid, the anode of one of said devices constituting the cathode of another of said devices and 90 constituting a sealing wall between said devices, and means simultaneously controlling the variation of the different potentials of said grids. 95

24. Thermionic apparatus comprising a 100 plurality of cooperating thermionic devices each comprising an anode, cathode and grid, the anode of one of said devices constituting the cathode of another of said devices, means for varying the potential of the grid of said one of said devices, and an inductive coupling between the grid circuit of said other of said devices and the anode circuit of said one of said devices. 105

25. Thermionic apparatus comprising a 110 plurality of cooperating thermionic devices each comprising an anode, cathode and grid, the anode of one of said devices constituting the cathode of another of said devices and constituting a sealing wall between said devices, means for varying the potential of the grid of said one of said devices, and means responsive to changes in the anode current of said one of said devices varying the potential of the grid of said other of said devices. 115

26. Thermionic apparatus comprising a 120 plurality of cooperating thermionic devices each comprising an anode, cathode and grid, the anode of one of said devices constituting the cathode of another of said devices, means simultaneously controlling the variation of the potentials of said grids, and an oscillation producing circuit including the anode 125 and cathode of said other of said devices.

27. Thermionic apparatus comprising co- 130 operating thermionic devices each comprising an anode, cathode and grid, the anode of one of said devices constituting the cathode

of another of said devices, means for varying the potential of the grid of said one of said devices, and means independently impressing upon the grid of said other of said devices a fluctuating or alternating potential.

28. Thermionic apparatus comprising thermionic devices each comprising an anode, cathode and grid, the anode of one of said devices constituting the cathode of another of said devices, telephonic means varying the potential of the grid of said one of said devices, the grids of said devices being independent of each other, and means responsive to current variations in the anode circuit of said one of said devices varying the potential of the grid of said other of said devices.

29. Thermionic apparatus comprising thermionic devices each comprising an anode, cathode and grid, the anode of one of said devices constituting the cathode of another of said devices, telephonic means varying the potential in the grid of said one of said devices, means responsive to current variations in the anode circuit of said one of said devices varying the potential of the grid of said other of said devices, and an oscillation producing circuit including the anode and cathode of said other of said devices.

30. Thermionic apparatus comprising thermionic devices each comprising an anode, cathode and grid, an anode of one of said devices constituting the cathode of another of said devices, telephonic means varying the potential of the grid of said one of said

devices, said grids being independent of each other, and a coupling between the grid circuit of said other of said devices and the anode circuit of said one of said devices. 40

31. Thermionic apparatus comprising thermionic devices each comprising an anode, cathode and grid, an anode of one of said devices constituting the cathode of another of said devices, telephonic means varying 45 the potential of the grid of said one of said devices, a coupling between the grid circuit of said other of said devices and the anode circuit of said one of said devices, and an oscillation producing circuit including the 50 anode and cathode of another of said devices.

32. Thermionic apparatus comprising a plurality of cooperating thermionic devices each comprising an anode, a cathode and a 55 grid, the anode of one of said devices being the cathode of another of said devices, and a transformer coupling the grid circuit of one of said devices to the anode circuit of another of said devices. 60

33. Thermionic apparatus comprising a plurality of cooperating thermionic devices each comprising an anode, a cathode and a grid, the anode of one of said devices being the cathode of another of said devices, and 65 means for normally holding one of said grids independently of the other at a predetermined negative potential.

In testimony whereof I have hereunto affixed my signature this 11th day of November, 1918.

CORNELIUS D. EHRET.
